UNITED STATES PATENT OFFICE

ALBERT J. GURNEY, OF CANTON, OHIO, ASSIGNOR TO THE AMERICAN MINE DOOR CO.,
OF CANTON, OHIO, A CORPORATION OF OHIO

OPERATING MECHANISM FOR MINE DOORS

Original application filed May 13, 1925, Serial No. 30,078. Divided and this application filed November 23, 1925. Serial No. 70,936.

This invention relates to an improved operating mechanism for mine doors, being a division of my co-pending application for automatic mine door filed May 13, 1925, Serial No. 30,078.

The invention seeks, among other objects, to provide an improved train-operated mechanism for swinging the wings of a mine door to open position and wherein the speed of the opening travel of the wings will, as said wings approach open position, be gradually reduced while, when the wings are open, the thrust of the wings tending to move to closed position will be partially counteracted, so that the wings may be readily held open.

Another object of the invention is to provide a novel mechanism including a counterweight for closing the wings and also including springs acting directly on the wings, and wherein the effectiveness of the counterweight will be decreased as the effectiveness of said springs is increased and vice versa, so that practically uniform tension will be exerted on the wings tending to urge the wings to closed position.

And the invention seeks, as a still further object, to provide an improved mounting for the free end of the door operating trip lever employed, and wherein said end of the lever may be adjustably elevated or lowered.

Other objects of the invention not specifically mentioned in the foregoing will appear during the course of the following description.

In the accompanying drawings:

Figure 1 is a horizontal sectional view taken through a mine door as disclosed in my prior application previously identified.

Figure 2 is a detail elevation showing one of the door closing springs.

Figure 3 is a fragmentary horizontal sectional view showing the position of the parts when the door wings are swung to open position.

Figure 4 is a fragmentary elevation particularly showing one of the door closing levers.

Figure 5 is a fragmentary plan view showing the operating mechanism in connection

with a mine track, this view also showing the location of the mine door.

Figure 6 is a detail sectional view on the line 6-6 of Figure 5, looking in the direction indicated by the arrows.

Figure 7 is a detail perspective view particularly showing the counterweight and associated parts.

Figure 8 is a detail sectional view on the line 8-8 of Figure 5, looking in the direction indicated by the arrows.

Figure 9 is a detail perspective view particularly showing the bed plate and associated parts employed at the free end of the trip lever of the operating mechanism.

Figure 10 is a detail perspective view showing one of the clamping jaws employed in connecting the plate with the adjacent rail of the track.

Figure 11 is a perspective view showing the companion clamping jaw employed.

Referring now more particularly to the drawings, I shall, in order that the function and operation of the present mechanism may be better understood, first describe the door structure. However, since the door shown in the present instance is identical with the door disclosed in my prior application previously identified, it is only necessary to herein generally note the structural features of the door rather than describe the door in detail.

A door frame 10 is employed and, as shown in Figure 5, this frame is erected diagonally of the mine track, which is conventionally illustrated at 11, bumpers 12 being provided at opposite sides of the track adjacent the door. Swingingly mounted in the door frame are mating door wings 13 overlapping at their outer vertical margins, and connected with said wings at their inner vertical margins are lower hub plates 14 having arms 15 which project laterally at one side of the door. Extending between said arms beneath the mine track, is a connecting rod 16 coupling the wings to simultaneously swing in opposite directions.

Coming now more particularly to the subject of the present invention, I employ, as seen in Figure 1, a pair of angle-shaped brackets 17 which are fixed to opposite cor-

55

responding corners of the side posts of the door frame at the lower ends of said posts, and projecting from the brackets are spaced arms 18. Swingly mounted upon the brackets are levers 19 provided medially with hubs 20 which are freely received between the arms 18 of the brackets and extending through the hubs and through the arms are pivot pins 21. Formed on the hub plates 14 of the door wings are arms 22 which extend at opposite sides of the door, and connecting the inner ends of the levers 19 with the free ends of said arms are links 23. As shown in Figure 1, the outer ends of the levers are curved toward the side posts of the door frame while the inner ends of the levers, as shown in Figure 4, are offset with respect to the outer ends of the levers to lie in a plane with the arms 22.

Attention is now directed to the fact that when the wings 13 are closed, as shown in Figure 1, the inner ends of the levers 19 stand substantially parallel to the arms 22 of the hub plates 14 of the door wings and, as will be seen, when the levers are swung, so that the inner ends thereof travel toward the wings, the wings will, as suggested in Figure 3, be swung in opposite directions to open position. As the wings are thus swung open, the levers 19 and the links 23 are swung toward an alined position so that when the wings are fully open, the links and levers occupy a relation close to dead center. Thus, a portion of the thrust of the wings tending to swing closed will be counteracted by the approximate dead center relation of the links and levers so that the wings may be readily held open while strain upon the mechanism connected with the levers will be relieved. Furthermore, the speed of the opening travel of the wings will, as will be seen, be gradually reduced as the wings approach the end of their opening travel so that banging of the wings against the bumpers 12 will be prevented.

Formed on the outer ends of the levers 19, as particularly shown in Figure 2, are upstanding arms 24 directed laterally over the upper ends of the hubs 20 of said levers, and fixed to said arms are upstanding centering studs or posts 25 axially alined with the hubs. Fixed to the side posts of the door frame above the brackets 17 are bracket plates 26 and projecting from each of said plates is a pair of arms 27. Journaled between said pairs of arms are ratchets 28 grooved to accommodate said arms and extending between the free ends of the arms are bolts 29 retaining the ratchets. Formed on the lower ends of the ratchets are studs 30 axially alined with the studs 25, and formed on the ratchets at the base of the studs 30 are laterally directed bosses 31. Fitting at their ends over the studs 25 and 30 are springs 32, the lower ends of which are engaged with the

arms 24 while the upper ends of said springs are engaged with the bosses 31. Pivoted upon the plates 26 to coact with the ratchets 28 are pawls 33 for locking the ratchets against retrograde movement, and formed in the upper end portions of the ratchets are circumferentially spaced openings 34 to selectively receive a pin, as suggested in dotted lines at 35. Thus, the ratchets may be conveniently turned for adjustably tensioning the springs 32 so that the springs will accordingly function to urge the wings 13 to closed position. As will be seen, the studs 25 and 30 engage the ends of the springs only while the intermediate portions of the springs are free. Friction is thus reduced to a minimum.

Duplicated at opposite sides of the door is the mechanism for operating the levers 19. A description of the mechanism at one side of the door only will, therefore, suffice for both. Secured to appropriately spaced ties of the mine track, near corresponding ends of said ties, as seen in detail in Figures 6 and 7 of the drawings, are pairs of spaced brackets 36, the innermost of which are provided with lateral slotted ears 37. Corresponding ears of the brackets project beneath the base flange of the adjacent track rail, and overlying said flange are clamping plates 38 abutting the brackets. Extending through the plates and through said ears are bolts 39 securing the brackets to the rail. Pivoted upon each pair of brackets is a pair of sleeves 40, the innermost of which are provided with laterally directed arms 41, and fitting through each pair of sleeves is a squared shaft 42 secured by set bolts 43. Pivots connected to the arms 41 of the innermost sleeves 40 are links 44, and swingingly supported by said links is a channel-shaped operating bar 45 lying near the inner side of the adjacent track rail. As shown in Figure 5, the bar 45 is formed of pivotally connected sections, the outermost of which provides a trip lever 46 which is inclined longitudinally and, as will be observed, the flange of the bar adjacent the rail is preferably shorter than the opposite flange of the bar.

Disposed between the adjacent ties of the track beneath the outer end portion of the lever 46, as best seen in Figures 8 and 9 of the drawings, is a channel-shaped bed plate 47 provided at its inner end with lateral wings 48 resting upon said ties and secured thereto. Straddling the outer end of said plate is a clamping jaw 49, shown in detail in Figure 10 of the drawings. This jaw is provided with parallel arms 50 and connecting said arms at their upper ends is a head 51 engaging over the base flange of the adjacent track rail at the outer side of the rail. Formed on the arms 50 at their inner sides are hooks 52 to embrace the lower edges of the side flanges of the bed plate 47 and formed on the lower ends of said arms are pairs of ears 53. Co-

operating with the jaw 49 is a pair of mating jaw members 54, shown in detail in Figure 11 of the drawings. These jaw members are arranged to extend at opposite sides of the bed plate 47 at the inner side of the rail and are formed at their upper ends with heads 55 to engage over the base flange of the rail. Projecting from the inner sides of said jaw members are hooks 56 to embrace the lower edges of the side flanges of the bed plate and, as brought out in Figure 8, the lower ends of the jaw members are formed to fit between the pairs of ears 53 at the lower ends of the arms 50 of the jaw 49. Extending through the upper ends of the arms 50 of the jaw 49 and through the upper ends of the jaw members 54, are bolts 57 lying at opposite sides of the bed plate and, as will be seen, when these bolts are tightened, the lower ends of the arms 50 and the lower ends of the jaw members 54 will rock against each other while the upper end of the jaw 49 as well as the upper ends of the jaw members 54 will be swung toward each other. Accordingly, the head 51 of the jaw 49 and the heads 55 of the jaw members 54 will be caused to bind against the base flange of the rail while the hooks 52 and 56 of said jaw and the jaw members will be swung up beneath the lower edges of the side flanges of the bed plate 47 for rigidly clamping the bed plate to the rail. Furthermore, as will be seen, the construction is such that the jaw and jaw members may be employed for clamping the bed plate to rails of different sizes.

Rising from the inner end of the bed plate 47 is a guide flange 58, at the base of which the plate is provided with an opening 59, and projecting into said opening at opposite ends thereof are V-shaped ribs 60 extending transversely of the upper end of said opening. Adjacent the opening 59, the plate is formed with transverse cross webs or partitions 61 and 62 between which extends a bottom wall 63 inclined transversely of the plate. This bottom wall cooperates with said partitions to form a seat for a bearing block 64 which is snugly received between the partitions and is formed with a beveled end 65 to rest flat against said bottom wall. Thus, by shifting the position of the block along the bottom wall 63 of the seat, the block may be adjustably elevated or lowered with respect to the bed plate, and formed on the partition 61 at its inner side are vertical teeth while the block is provided with mating teeth 66 to coact with the former teeth for locking the block in adjusted position. Fixed to the trip lever 46 near its free end is a depending retaining post 67 which is freely received through the opening 59 of the bed plate between the ribs 60 so that as the trip lever is rocked said post will pivot against said ribs, and extending from the post transversely beneath the lever is a substantially V-shaped

fulcrum rib 68 resting upon the upper end of the bearing block 64. The rib 68 will thus coact with the block for pivotally supporting the lever 46 for free rocking movement while the bearing block may be adjusted upon the bed plate 47, as previously explained, for elevating or lowering the outer end of the lever. Engaged through the lower end of the post 67 is a key or like device 69 limiting the post against upward displacement and, as will be seen, the flange 58 of the bed plate is disposed to coact with the upper end of the post for bracing the post and holding the outer end of the lever 46 against lateral displacement away from the track rail.

Adjustably fixed to the outer end portions of the shafts 42 are upstanding arms 70, and pivotally connected to the upper end of the forwardly disposed arm, as seen in Figure 5, is a clevis 71 in which slides a cross head 72. Extending from the cross head through the forward end of the clevis is a rod 73 pivotally connected to the outer end of the lever 19 at the adjacent side of the door. A like rod is, of course, connected to the lever 19 disposed at the opposite side of the door. Surrounding the rod 73 is a cushioning spring 74 bearing between the forward end of the clevis and the cross head, and pivotally connected to the rear end of the clevis is a rod 75. A similar clevis 76 is connected to the rearwardly disposed arm 70 furthest remote from the door, and slidable in said clevis is a cross head 77 to which is connected a rod 78, while a cushioning spring 79 is disposed to bear between the forward end of the clevis and the cross head. Pivotally connected to the upper end of that one of the arms 70 disposed between the forward and rear arms are links 80 to which are attached rods 81, and connecting said rods with the rods 75 and 78 are turnbuckles 82. Thus, the arms 70 of the shafts 42 are operatively connected with the lever 19 and, as will now be seen, a car traveling on the track 11 toward the door will first engage and depress the lever 46, when said shafts will be rocked for swinging the door wings 13 to open position. As the car nears the door, the operating bar 45 will be held depressed by the car for maintaining the door wings in open position and before the wheels at one side of the car move out of engagement with the bar 45 at one side of the door, the wheels at the opposite side of the car will engage the bar 45 at the other side of the door so that the door wings cannot close until the car has cleared the latter bar. The cushioning springs 74 and 79 will, of course, tend to absorb the shock of the impact of the car wheels with the trip lever 46.

Adjustably fixed to the outer end of one of the shafts 42, as particularly shown in Figure 7, is a sleeve 83 on which is formed an angularly disposed socket 84, and fixed at its lower end in said socket is an arm 85. Ad-

justable along the arm is a counterweight 86. When the operating bar 45 is depressed and the shafts 42 are rotated for opening the door, the arm 85 will be swung up to a position closely approaching the vertical so that the effectiveness of the counterweight tending to counter-rotate said shafts will be correspondingly reduced. However, as the door wings 13 are swung open by the depression of the operating bar 45, the tension on the springs 32 will be increased so that the effectiveness of said springs tending to urge the door wings to closed position will be correspondingly increased. On the contrary, when the operating bar 45 is released, the arm 85 will swing downwardly toward a horizontal position so that the effectiveness of the counterweight 86 for maintaining the door wings closed will be correspondingly increased. However, the effectiveness of the door springs 32 will, due to the lessening of the tension on said springs by the closing of the door wings, be correspondingly decreased. Thus, the counterweight and door springs will function in conjunction with each other to maintain a substantially uniform tension on the door wings tending to urge said wings to closed position. As the arm 85 is swung downwardly by the counterweight 86, the shafts 42 will, of course, be counter-rotated for elevating the operating bar 45 and trip lever 46 to their normal position with respect to the adjacent track rail.

Having thus described the invention, what I claim is:

1. In a mine door, mating swingingly mounted door wings, means connecting said wings to swing in unison, a lever pivoted at a point between its ends to swing in a plane with said wings, means connecting the inner end of said lever with one of said wings, the inner end of the lever being movable toward said wing for opening the wings, and train operated means connected to the outer end of said lever for swinging the lever.

2. In a mine door, mating swingingly mounted door wings, means connecting said wings to swing in unison, an arm movable with one of said wings, a lever pivotally mounted to swing in a plane with said wings, a link connecting the inner end of said lever with said arm, the inner end of the lever being movable toward said wing for opening the wings, and train operated means connected with the outer end of said lever for swinging the lever.

3. In a mine door, mating swingingly mounted door wings, means connecting said wings to swing in unison, including a lever for swinging the wings to open position and operable to gradually reduce the rate of opening movement of the wings as said wings approach the end of their opening travel, without a reduction in the rate of travel of said

lever, and train operated means connected with said lever for swinging the lever.

4. In a mine door, mating swingingly mounted door wings, means connecting said wings to swing in unison, coacting pivotally connected means for opening said wings and movable to closely approach a position locking the wings open, and train operated means connected with said last mentioned means for opening the wings.

5. In a mine door, mating swingingly mounted door wings, means connecting said wings to swing in unison, means for opening said wings including a pivoted lever and connecting link movable to closely approach an aligned position for maintaining the wings open, and train operated means connected with said lever for swinging the lever.

6. In a mine door, mating door wings, upper and lower hub plates carried by said wings and provided with means swingingly mounting the wings, the lower hub plates being provided with long arms and short arms, means extending between the long arms connecting the wings to swing in unison, pivotally mounted levers, links connecting the inner ends of the levers with said short arms, the levers being movable for swinging the wings to open position, and train operated means connected with the outer ends of said levers for swinging the levers.

7. In a mine door, mating swingingly mounted door wings, means connecting said wings to swing in unison, means for opening said wings including a lever, a torsion spring connected with said lever for urging the wings to closed position, and train operated means connected with said lever for swinging the lever.

8. In a mine door, mating swingingly mounted door wings, means connecting said wings to swing in unison, means for opening the wings including a pivotally mounted lever, an arm carried by said lever, a fixed bracket plate, a ratchet carried by said plate, a torsion spring engaged at one end with said arm and at its opposite end with said ratchet for urging the wings to closed position, the ratchet being adjustable for tensioning said spring, and train operated means connected with said lever for swinging the lever.

9. In a mine door, mating swingingly mounted door wings, means connecting the wings to swing in unison, a torsion spring urging the wings to closed position, train operated mechanism for opening the wings, and a counterweight associated with said operating mechanism and functioning in conjunction with said spring to maintain a substantially uniform tension on the wings tending to close said wings.

10. In a mine door, mating swingingly mounted door wings, means connecting said wings to swing in unison, a torsion spring tending to close the wings and connected with

one of said wings whereby the tension of said spring is increased as the wings are opened, train operated mechanism for opening the wings, a lever operable by said mechanism, 5 and a counterweight carried by the lever, the lever being movable toward vertical position as the wings are opened whereby the effectiveness of the counterweight tending to close the wings is decreased as the tension of said 10 spring is increased and vice versa.

11. In a mine door, mating door wings, and train operated mechanism for opening the wings including a trip lever, a bed plate having an inclined wall, and a bearing block pivotally supporting the outer end of the lever 15 and adjustable along said wall for elevating said end of the lever.

12. In a mine door, mating door wings, and train operated mechanism for opening said 20 wings including a trip lever, a bed plate having a seat provided with an inclined bottom wall and having a side wall provided with teeth, and a bearing block received in said seat to rest against the inclined wall thereof and 25 provided with teeth to coact with said first mentioned teeth for locking the block in adjusted position along said wall, the block pivotally supporting the outer end of said lever and being adjustable for elevating said end of 30 the lever.

13. In a mine door, mating door wings, train operated mechanism for opening said wings including a trip lever, a bed plate disposed beneath a track rail, means carried by the bed 35 plate supporting the outer end of said lever, coacting jaws fulcruming against each other at their lower ends and engaging at their upper ends over a track rail, the jaws being provided with means to engage the bed plate, 40 and means for swinging the jaws toward each other and clamping the plate against the rail.

14. A mine door including mating door wings, and train operated mechanism for opening said wings including a trip lever, a bed plate disposed beneath a track rail and having side flanges, means carried by said 45 plate supporting the outer end of said lever, coacting jaws fulcruming against each other at their lower ends and engaging at their upper ends over the base flange of said rail, the 50 jaws being provided with hooks to engage the side flanges of said bed plate, and bolts extending between the jaws and adjustable for swinging the upper ends of the jaws toward each other and binding the bed plate against 55 said rail.

15. In a mine door, mating door wings, train operated mechanism for opening said wings including a trip lever, a bed plate having an inclined wall and an adjacent wall provided with teeth, and a bearing block pivotally supporting the outer end of the lever and adjustable along said inclined wall for elevating said end of the lever, the bearing 60 block being provided with teeth coacting with 55

said first mentioned teeth for locking the block in adjusted position.

16. In mine door train operated mechanism, a bed plate for supporting a trip lever adjacent a track rail, and coacting jaws fulcrumed upon each other to coact with the rail and said plate for clamping the plate to the rail. 70

17. In mine door train operated mechanism, a bed plate for supporting a trip lever 75 adjacent a track rail, mating jaws fulcrumed upon each other at corresponding ends thereof to coact at their opposite corresponding ends with the rail and provided between the ends thereof with means to coact with the bed 80 plate for binding the bed plate against the rail as the latter ends of the jaws are swung toward each other, and means for adjustably swinging the latter ends of the jaws toward each other. 85

18. In mine door train operated mechanism, a bed plate for supporting a trip lever adjacent a track rail and provided with side flanges, coacting jaws fulcrumed upon each other at corresponding ends thereof to coact 90 at their opposite corresponding ends with the rail and provided between the ends thereof with hooks to coact with the side flanges of the bed plate for binding the bed plate against the rail as the latter ends of the jaws 95 are swung toward each other, and means for adjustably swinging the latter ends of the jaws toward each other.

19. In mine door train operated mechanism, a bed plate for supporting a trip lever 100 adjacent a track rail, coacting jaws straddling the bed plate to engage the rail at their upper ends and fulcrumed upon each other at their lower ends, said jaws being provided between the ends thereof with portions to coact 105 with the bed plate for binding the bed plate against the rail as the upper ends of the jaws are swung toward each other in engagement with the rail, and means extending between the jaws for swinging the upper ends thereof 110 toward each other. 115

In testimony whereof I affix my signature.

ALBERT J. GURNEY. [L.S.]
